INCANDESCENT LAMP

Giovanni Piersimoni, New York, and Henry S. Friedman, Mount Vernon, N. Y., assignors to Multi-Lite Corporation, New York, N. Y., a corporation of New York

Application March 20, 1933, Serial No. 661,742

3 Claims. (Cl. 176—27)

This invention relates to incandescent lamps and it more particularly relates to incandescent lamps of the multiple filament type.

One object of this invention is to provide a lamp having a plurality of lighting filaments in its bulb, the filaments and their lead wires being arranged in such manner that electric current may be passed selectively through one filament independent of the others and that at will all or part of the other filaments may be energized at the same time if more light is needed than one filament can furnish.

It is another object of the invention to provide an electric lamp having a plurality of lighting filaments arranged in such manner that the danger of a short circuit is practically eliminated.

With these general objects in view, an important feature of the invention relates to the provision of an improved form of a cap or base, which extends from the neck of the bulb and contains all the passageways for the switches which regulate the various circuits for energizing the filaments. The base also covers the tube through which the air in the bulb may be exhausted, so that a vacuum may be formed within the bulb without marring the smooth shape of the bulb.

Other features of the invention relate to other arrangements and combinations of parts which will be hereinafter described and more particularly pointed out in the appended claims.

A preferred form of the invention is shown in the drawing in which

Figure 1 is a longitudinal sectional view through the improved lamp,

Figure 2 is a longitudinal sectional view of a modified form of a lamp,

Figure 3 is a fragmentary detail view showing a dove tail groove adapted to receive the switch arrangement,

Figure 4 is a fragmentary detail view of another form of a switch arrangement, and

Figures 5 and 6 indicate diagrammatically the arrangements for the increase of the number of filaments.

The same numerals denote like parts throughout the drawing.

Referring to the drawing the numeral 10 denotes the bulb of the lamp, which is made of glass, transparent, frosted or colored. A stem or tube 11 is arranged longitudinally within the bulb 10 and is welded near its upper end to the edges of the same. The tube 11 is initially open at both its outer and inner ends so that before it is welded to the bulb 10 certain wires, which are specified further below, may operatively be arranged within said tube 11. After the welding the air is exhausted from the bulb 10; the air escapes through the aperture 12 provided in the

tube 11, which is finally sealed in the well known way after the vacuum has been established.

An inspection of Figure 1 shows that the insulating filler 14, which may consist of any cementitious or other suitable agent, fixes the shell 15, which is for instance made of brass, tightly upon the bulb 10 around one end of the tube 11. Contacts 17 are arranged upon a plate 16 of any insulating material and wires 18 and 19 extend from these spaced contacts through the tube 11 from which their inner ends project into the bulb 10.

At 20 a wire 21 contacts with shell 15 and extends from there through the tube 11 and issues into bulb 10 in the same manner as the wires 18 and 19.

A branch-wire 22 extends from the wire 21 and a filament 23 connects the end of this branch-wire 22 with that of the wire 19. Another filament 24 connects the ends of the wires 18 and 21.

Bayonet pins 25 extend through the side walls of the shell 15. From Figure 1 it will be noticed that the wire 18 extends slightly beyond the plate 16 and that a flat spring 26, with a lug attached thereto at one of its ends, is rotarily arranged upon said plate 16 and is held thereagainst by the flattened end 27 of the wire 18. The spring 26 may be turned from its normal position, indicated by dotted lines, so that its lug 30 presses upon the contact 17 at the end of wire 19, if it is desired to close the circuit of which the conductor wire 19 forms a part.

When this improved bulb is in use, the shell 15 is fitted into a lamp socket with the bayonet pins 25 engaged in slots formed in the walls thereof in the usual manner. When the switch is turned on, the current passes inwardly through the contact 20 and leaves through 21, whereby the filament 24 is energized; in this case spring 26 is on 40 the contact 17 at the end of wire 18 and is in the position indicated by the dotted lines. In case the filament 24 burns out, the spring 26 is turned around so as to touch the contact 17 at the end of wire 19, whereby the filament 23 is 45 energized.

In Figure 2 a modified form of the invention is shown wherein the construction is similar to that shown in Figure 1, insofar as a pair of filaments have been provided which are energized 50 by wires, of which two are branches of the positive wire. Each of the branch-wires of the positive wire is connected by way of a filament with one of the return wires, so that there are two circuits, of which one is immediately energized as 55 soon as the current of an electrical source, such as a battery, is switched on, whereas the other circuit can only be energized by actuating a switch provided at the base of the lamp.

In this modification a cap or base 29, made of 60

- insulating material, such as bakelite or other phenol-formaldehyde condensation products, or urea-formaldehyde, or other similar material, is secured by a non-conductive cement, or another similar agent, upon the bulb 10 around its lower end. Centrally upon the bottom of the base 29 there is arranged a contact 30, from which a wire 31 extends and branches out into the two parallel wires 32 and 33.
- 10 Two return wires 34 and 35 are arranged parallel on the outer sides of wires 32 and 33, respectively; the outer end of the wire 35 is drawn out between the bulb 10 and the rim of the base 29 and is connected at 36 with a metal strip 37 which 15 is retained by a flattened bayonet pin 38 within one of the grooves 39, cut longitudinally into the base 29 on opposite sides thereof.

In another groove 39 there is arranged a metal strip 40 provided with a slot 41, through which a 20 flattened bayonet pin 38 passes so as to hold the metal strip or switch 40 tightly, but slidably in the groove 39.

At the end of the groove 39 which accommodates the switch 40, is arranged a contact 42, to 25 which the outward end of the wire 34, passing through between the bulb 10 and the rim of base 29, is connected. In order to make a good connection with this contact 42, the switch 40 is provided at its adjoining end with a slight dent 30 which will come to press upon contact 42 when the switch 40 is shifted upwardly.

For purposes of reinforcement and alignment the wires 34, 32, 33 and 35 are embedded in a glass bead 43. A filament 44 connects the inner ends 35 of wires 34 and 32 and a filament 45 connects those of the wires 33 and 35.

When this improved bulb is fitted into a lamp socket with the pins 38 engaged in slots formed in the walls thereof in the usual manner, the 40 switch 40 is off contact 42 and therefore the filament 45 will be energized; should this filament burn out, the bulb is taken out and the switch 40 shifted upon contact 42, and upon re-insertion of the bulb into the lamp socket, the filament 44 45 will be energized.

Instead of a groove of a rectangular cross-section, as has been shown in groove 39, I may construct the groove so as to have a dove-tail cross-section as illustrated by Figure 3. There 50 the base is provided with a channel 47 of dove-tail cross-section, which slidably accommodates sheet metal or switch 48. From an inspection of Figure 3 it will be noticed that the switch 48, suitably of brass, has its edges bent up so as to 55 form a slide of dove-tail cross-section, which will fit into channel 47; as its sides display some spring action and touch the adjoining walls, the friction between these parts holds, or contributes to hold, the switch 48 in place. Projections 49 facilitate the shifting of switch 48 in the well known way.

In Figure 4 there has been shown a further modified form of switch construction in connection with the contact 42 shown in Figure 2, 65 from which it is obvious that a strip of metal, or switch 50, is hingedly connected with the pin 38 and normally rests within the groove 51 which is sunk into the peripheral face of the base 29 substantially parallel to its upper rim. The switch 70 50 is of arcuate form so as to conform to the peripheral surface of base 29 and has a scoop-like terminal with a lateral projection to facilitate

its manipulation. Another groove 52 receives the contact 42 and communicates with the groove 51 so that the switch 50 may be turned to engage contact 42.

On account of the arcuate form of the switch 5 50, the same also displays some spring action when turned into the groove 52 and its scoop-shaped terminal is therefore tightly pressed upon contact 42.

It is, of course, understood that the construction 10 of our new incandescent lamps is not restricted to arrangements with two filaments only, but that with the increase in the size of the lamps we may increase the number of lateral contacts 15 17, which would all be arranged in an annular path, so that the lug of the rotarily arranged spring 26 may consecutively connect to each of the contacts 17. As diagrammatically shown in Figure 6 there may be many of these contacts 17 as long as the spring may be conveniently positioned between two such contacts 17 without contacting with the same if not desired.

We are also not restricted in the number of independent wires, such as 33 and 34, as is self-evident from Figure 5, where we show that, dependent 25 on the length of the circumference of the base 29, we can provide a number of grooves 39 to receive contacts 42 connected with the independent wires.

In both cases the filaments connecting the ends 30 of the wires with the ends of the branch wires are very much more apart from each other so that at the burning out of one wire none of the others are affected.

What we claim is:

1. In an incandescent multiple filament lamp 35 the combination of a bulb, a base of insulative material secured to the bulb at its end, a plurality of grooves arranged longitudinally of the base, a bayonet pin arranged within each of said grooves, 40 a contact arranged upon said base, a wire extending from said contact and branching into a plurality of wires, a metal strip rigidly held in one of aforesaid grooves by a bayonet pin, a metal strip held slidably arranged by a bayonet pin in 45 each of the other of aforesaid grooves, a contact within each of said grooves, a plurality of independent wires extending along aforesaid branch wires, one of said independent wires connecting with the aforesaid rigidly held metal strip and 50 one each of the others with the contact in the other grooves, and filaments connecting pairs of the ends of the independent and of the branch wires.

2. In an incandescent lamp provided with filaments, a bayonet base and terminals on said base by way of which current is admitted to said lamp, a movable contact member on the cylindrical surface of said base electrically connected with one of said terminals, and slideable upon said surface 60 between contact make and break positions, and a second contact member in make and break alignment with said first member and electrically connected with one of said filaments.

3. In an incandescent lamp provided with multiple filaments and a bayonet pin base, a switch forming part of said base, movably retained by one of the bayonet pins of said base and comprised in the circuit of one of said filaments within said lamp.
